SPLINT

Earl E. Longfellow, Warsaw, Ind., assignor to
Harry H. Leiter, Warsaw, Ind.

Application July 2, 1938, Serial No. 217,231

4 Claims. (Cl. 128—88)

My invention relates to splints, and more particularly to improvements in splints utilized in the treatment of fractures which necessitate the holding of an upper limb in a fixed position with respect to the body.

It is an object of my invention to provide an adjustable support for holding a patient's arm in a fixed position with respect to the body, which support insures greater comfort and ease of the patient by providing a substantially smooth and continuous padded surface adjacent to the patient's body and supporting the upper arm.

Another object of my invention is to provide an improved splint adaptable for mounting on either side of a patient's body and having parts, adjustable to the physical dimensions of the patient as well as adjustable to a wide variety of positions, for securing the patient's upper arm and forearm in fixed positions with respect to the body.

Other objects, features and advantages of my invention will be apparent from the following description and the drawings wherein a preferred embodiment of my invention is clearly shown and described.

In the drawings:

Fig. 1 is a perspective view of a preferred embodiment of my invention and indicates the adaptation thereof to a patient's body and arm;

Fig. 2 is a sectional view taken substantially on the line 2—2 of Fig. 1 and looking in the direction of the arrows;

Fig. 3 is a view taken substantially on the line 3—3 of Fig. 2 and looking in the direction of the arrows; and

Fig. 4 is a view taken substantially on a line 4—4 of Fig. 2 and looking in the direction of the arrows.

With particular reference to the drawings, an anchor member 1 comprises a plate having ventilating openings, such as 2 and a concave inner surface 3 adapted to fit the side of a patient's body and extend practically from the hip to the arm pit of the patient; an outwardly curved edge portion being provided at 4 to increase the comfort of the wearer and to prevent chafing. Buckles 5, 6, 7, 8, 9, and 10 are secured to the outer surface of the anchor member 1 by rivets, such as 11 or other suitable fastening means. The buckles 5, 6, 7, 8, 9, and 10 co-operate with straps 12, 13, and 14 to hold the anchor member in position against the body of a patient substantially as indicated in Fig. 1 where the body and arms are shown in dotted lines, as at 15. The straps 12, 13, and 14 are preferably provided with pads 16,

17, and 18, respectively, of felt or other suitable material which prevents the straps from directly engaging the patient's body and thus lend greater comfort to the wearer.

An upper arm support or cradle 20 is connected to the anchor member 1 by a hinge 21 that is secured to the upper arm support or cradle 20 and the anchor member 1 by rivets 22, or other suitable means. The anchor member 1 and upper arm support or cradle 20 are preferably fluted 10 as at 23 and 24, respectively, adjacent the hinge 21 to increase the rigidity thereof. The upper arm support or cradle 20 has a concave surface 25 for supporting the upper arm of the patient. The concave surfaces 3 of the anchor member 1 and 25 of the upper arm support or cradle 20 are covered by a single pad 26 of felt or other suitable material which is held in place by ties such as 27. The pad 26 preferably extends beyond the edges of the anchor member 1 and upper arm support or cradle 20 to prevent possibility of contact between the metal parts of the anchor member 1 and upper arm support or cradle 20 and the patient. The use of the single pad 26 for both the anchor member 1 and the upper arm support or cradle 20 provides a continuous and substantially smooth inner surface adjacent the patient's body and thereby minimizes the possibility of chafing.

A reinforcing strip 29 is secured to the outer surface of the anchor member 1 by rivets 30. This reinforcing strip 29 extends longitudinally of the anchor member 1 and is preferably located substantially midway between the sides of the anchor member. An extension strip 31 is secured to the upper arm support or cradle 20 by rivets 32 and 33 and extends beyond the end of the upper arm support or cradle. The extension strip 31 and reinforcing strip 29 both extend substantially perpendicular to the axis of the hinge 21 and preferably have substantially co-planer longitudinal center lines. A strut or brace comprising a turnbuckle 34 is fulcrumed at its ends, as at 35 and 36, to hinge brackets 37 and 38, respectively. The hinge bracket 37 is secured to 45 the extension strip 31 and upper arm support or cradle 20 by the rivet 32. The hinge bracket 38 is secured to a plate 39 by a rivet 40. A wing bolt 41 extends through an opening in the plate 39 and is threaded into the opening 42 in the 50 reinforcing strip 29 and anchor member 1. The wing bolt 41 is also adapted to be threaded into openings 43 or 44 in the reinforcing strip 29 and anchor member 1 to vary the distance of the hinge bracket 38 from the hinge 21 and thereby effect a 55

rough adjustment of the angular position of the upper arm support or cradle 20 with respect to the anchor member 1. The distance between the openings 42, 43, and 44 is preferably so related to the design of the turnbuckle 34 that adjustment of the turnbuckle accomplishes adjustment of the angular position of the upper arm support or cradle 20, with respect to the anchor member 1, to any position between the extremes 10 provided by movement of the plate 39 and wing bolt 41. A forearm support strip 45 is adjustably secured at one end to the extension strip 31 by a bolt 46 which extends through an opening 47 in the forearm support strip 45 and through a 15 longitudinal slot 48 in the extension strip 31 to provide a fulcrum for the forearm support strip 45; the forearm support strip 45 also being adjustable longitudinally of the extension strip 31 by movement of the bolt 46 in the slot 48. A wing 20 nut 49 on the bolt 46 serves to secure the position of the forearm support strip 45 with respect to the extension strip 31.

A brace 50 is fulcrumed to the extension strip 31 and upper arm support or cradle 20 by the 25 rivet 32 and has a longitudinal slot 51 therein. A wing bolt 52 extends through the slot 51 and is threaded into the forearm support strip 45. The brace 50, being angularly disposed with respect to the extension strip 31 and forearm support strip 45 and being fulcrumed to the extension strip 31 and adjustably secured to the forearm support strip 45 by the wing bolt 52, provides an additional means for positively determining the position of the forearm support strip 35 45 with respect to the extension strip 31.

The forearm support strip 45 has a forearm cradle 53 adjustably secured thereto by a pair of bolts 54 and 55 that extend through a longitudinal slot 56 in the forearm support strip 45 and have co-operating wing nuts 57 and 58, respectively. The forearm cradle 53 is preferably provided with ventilating openings, such as 59, and has an integral hand rest 60. The forearm cradle 53 is preferably fluted at 61 between the hand rest 60 and the forearm support strip 45 to increase the rigidity thereof.

A substantially L-shaped hitch support 62 is secured to the extension strip 31 by a pair of wing bolts 63 and 64 and extends longitudinally outward from the ends of the extension strip 31. The L-shaped hitch support 62 has openings 65 and 66 in an angularly extending portion 67 thereof. An eyebolt 68 extends through the opening 65 and is provided with a co-operating wing nut 69 and a washer 70.

The eyebolt 68 supports a hitch member 71 and preferably has a compression spring 72 surrounding a portion thereof between the angularly extending portion 67 of the L-shaped hitch support 62 and the washer 70. The hitch member 71 is adapted to hold the end of a strap 73 in tension for applying tractive force to the upper arm when such tractive force is necessary or desirable.

In the use of the device disclosed and described herein, after the anchor member 1 is firmly secured in position with respect to the body of the patient, the angular relation between the upper arm and body is adjusted and determined by determining the position of the plate 39 with respect to the reinforcing strip 29 and by adjustment of the turnbuckle 34. When the wing bolt 52 and the wing nut 49 are loosened, the forearm support strip is moved longitudinally of the extension strip 31 to effect adjustment corresponding to the length of the upper arm. At the

same time the angular relation of the forearm with respect to the upper arm is determined by the angular adjustment of the forearm support strip 45. After such adjustment, the wing bolt 52 and wing nut 49 are tightened to secure firmly the forearm support strip in place. The forearm cradle 53 is adjusted longitudinally of the forearm support strip 45 to correspond to the length of the forearm and properly place the hand rest 60. The entire device being practically symmetrical except for the direction at which the forearm support 45 extends from the extension strip 31, mounting is accomplished on either side of the patient by merely reversing the direction of the forearm support strip 45.

15

While I have illustrated and described a preferred embodiment of my invention, many modifications may be made without departing from the spirit of the invention and I do not wish to be limited to the precise details set forth but desire to avail myself of all changes within the scope of the appended claims.

I claim:

1. In a surgical appliance, the combination comprising, an upper arm support comprehending means having a slot therein extending longitudinally of the upper arm support, a forearm support comprehending manually adjustable clamping means rotatable and slidable in said slot, said forearm support having manually adjustable means to enable variations in the length thereof independently of the manually adjustable clamping means, a brace pivoted to one of the supports and having a longitudinal slot therein, and manually adjustable clamping means extending through the slot in the brace for securing the brace and the supports in fixed angular relation.

35

2. In a surgical appliance, the combination comprising, an anchor member having a concave inner surface, an upper arm support having a concave inner surface, a hinge connecting said member and support, and a pad secured to the concave inner surfaces of the member and support to provide a continuous padded inner surface.

40

3. In a splint, the combination comprising, an upper arm support, a bar secured at one end to said upper arm support and extending substantially parallel to the medial line of a patient's upper arm when the arm is positioned in said upper arm support, said bar having a longitudinal slot therein positioned opposite the elbow of the patient, a forearm support comprising a rod having an aperture through the lower end thereof, adjustable pivot means extending through said aperture and through said slot to permit the lower end of said forearm support to be shifted longitudinally of said bar to bring said lower end opposite the elbow of the patient, said forearm support having adjustable slotted means to permit variations in the length thereof after the position of the lower end of said forearm support is fixed, and an adjustable locking member extending between the forearm support and the bar to permit pivotal movement of said forearm support about the adjustable pivot means when loosened and to secure said forearm support rigid with respect to said bar when tightened, said pivotal movement being accomplished without movement of said pivot point with respect to the patient's elbow.

55

4. In a splint, the combination comprising, an anchor member, an upper arm support hinged to the anchor member, a bar secured at one end to

75

said upper arm support and extending substantially parallel to the medial line of a patient's upper arm when the arm is positioned in said upper arm support, said bar having a longitudinal slot therein positioned opposite the elbow of the patient, a forearm support comprising a rod having an aperture through the lower end thereof, adjustable pivot means extending through said aperture and through said slot to permit the lower end of said forearm support to be shifted longitudinally of said bar to bring said lower end opposite the elbow of the patient, said forearm support having adjustable slotted means to permit variations in the length thereof after the position of the lower end of said forearm support is fixed, and an adjustable locking member extending between the forearm support and the

bar to permit pivotal movement of said forearm support about the adjustable pivot means when loosened and to secure said forearm support rigid with respect to said bar when tightened, said pivotal movement being accomplished without movement of said pivot point with respect to the patient's elbow, an adjustable bracing member extending between the anchor member and the upper arm support, said bracing member being attached to the upper arm support by a single rivet passing through the adjustable bracing member, the lower end of the adjustable locking member, the upper arm support bar, and the upper arm support, whereby said rivet serves to anchor the several elements and forms a pivot for the adjustable locking member.

EARL E. LONGFELLOW.
